UNITED STATES PATENT OFFICE.

ABRAHAM SOLOMON, OF NEW YORK, N. Y.

MARKING-GAGE.

No. 867,761.

Specification of Letters Patent.

Patented Oct. 8, 1907.

Application filed May 16, 1907. Serial No. 373,927.

To all whom it may concern:

Be it known that I, ABRAHAM SOLOMON, a subject of the Czar of Russia, and a resident of the city of New York, borough of the Bronx, in the county and State 5 of New York, have invented a new and Improved Marking-Gage, of which the following is a full, clear, and exact description.

The object of the invention is to provide a new and improved marking gage more especially designed for 10 the use of carpenters, joiners, cabinet makers and other mechanics and artisans, and arranged to permit of conveniently and accurately laying out mortises and the like.

The invention consists of novel features and parts 15 and combinations of the same, which will be more fully described hereinafter and then pointed out in the claims.

A practical embodiment of the invention is represented in the accompanying drawings forming a part 20 of this specification, in which similar characters of reference indicate corresponding parts in all the views.

Figure 1 is a perspective view of the improvement; Fig. 2 is a side elevation of the same, parts being in section; Fig. 3 is an end elevation of the same, parts of 25 the stock being in section; and Fig. 4 is a plan view of the improvement.

In the stock or body A, of the marking gage are formed longitudinally extending recesses B and B' reaching from one end of the stock to the other end 30 thereof, and connected by longitudinal face slots B² with the faces of the stock, and by longitudinal side slots B³ with the sides of the stock.

In each of the guideways B, B' are fitted and mounted to slide a number of markers C, each having oppositely disposed points C', one of which is adapted to extend at a time through the top slot B², to project slightly above the corresponding face of the stock A, to make a scratch line when using the gage in laying out mortises and the like. By having each marker C 40 provided with two points C' the marker can be readily reversed in case one of the points is worn out or has become too dull for use.

In each of the markers C screws a clamping screw D extending through the side slot B³ to the other side of 45 the stock A. Now in order to bring the point of a marker C into a desired position, the operator takes hold of the outer or handle end of the clamping screw D of the marker and moves the latter to the desired position in the guideway B or B', and then screws up

the clamping screw D to clamp the marker in place in 50 the adjusted position.

Each face of the stock A is provided at its sides with longitudinally extending flanges A' forming guideways for the abutment bars E to slide on, each abutment bar extending transversely across the corresponding 55 stock face and being adapted to be secured in an adjusted position by a set screw F.

As illustrated in the drawings each guideway B and B' is provided with three markers C, but more or less markers may be employed according to the nature of 60 the work in hand.

The markers C in each guideway B, B' are set independently one of the other according to the work in hand, that is, the set of markers in one guideway may be set to mark the vertical lines for a mortise while the 65 markers in the other guideway may be set to give the width of the mortise. By the use of the abutment bars E the points C' are brought the desired distance from the edge of the wood on which the gage is used. In order to allow close adjustment of adjacent markers 70 C in a guideway B or B', the clamping screws D of such adjacent markers extend in opposite directions through the slots B², as plainly indicated in the drawings, thus leaving sufficient room for the operator to conveniently turn the clamping screws D for clamping 75 or unclamping the pointers in their respective guideways B or B'.

The marking gage shown and described is very simple and durable in construction, and the markers C and the abutment bars E can be quickly adjusted to suit the 80 work in hand.

Having thus described my invention, I claim as new and desire to secure by Letters Patent:

1. A marking gage comprising a stock provided with a longitudinal guideway having a face slot and a side slot, a 85 plurality of independent markers mounted to slide in the said guideway and having their points extending through the said face slot, and clamping screws engaging the markers, extending through the said side slot to fasten the markers in place in the guideway.

2. A marking gage comprising a stock provided with a longitudinal guideway having a face slot and a side slot, markers mounted to slide in the said guideway and having their points extending through the said face slot, clamping screws engaging the markers and extending through the 95 said side slot to fasten the marker in place in the guideway, and an abutment bar held adjustably on the face of the stock.

3. A marking gage comprising a stock, a guideway formed lengthwise in the stock and having a face slot and 100 a side slot, markers slidingly fitting the said guideway and

having double points for extending through the said face slot, and clamping screws engaging the markers and extending through the said side slot.

4. A marking gage comprising a stock, a guideway 5 formed lengthwise in the stock and having a face slot and a side slot, markers slidably fitting the said guideway and having double points for extending through the said face slot, clamping screws engaging the markers and extending through the said side slot, a guideway on the surface of the

stock, an abutment bar slidably mounted on the said surface guideway, and a set screw for securing the abutment bar in position. 10

In testimony whereof I have signed my name to this specification in the presence of two subscribing witnesses.

ABRAHAM SOLOMON.
